(57) **CLAIM**

The ornamental design for a storage device for a mobile device, as shown and described.

DESCRIPTION

FIG. 1 is a front perspective view of a storage device for a mobile device;

FIG. 2 is a first side view of the storage device for a mobile device shown in FIG. 1;

FIG. 3 is a front view of the storage device for a mobile device shown in FIG. 1;

FIG. 4 is a second side view of the storage device for a mobile device shown in FIG. 1;

FIG. 5 is a top view of the storage device for a mobile device shown in FIG. 1;

FIG. 6 is a bottom view of the storage device for a mobile device shown in FIG. 1; and,

FIG. 7 is a back view of the storage device for a mobile device shown in FIG. 1.

The broken lines shown in the figures are for illustrative purposes only and form no part of the claimed design.
